(57) **CLAIM**

The ornamental design for a solar handbag, as shown and described.

DESCRIPTION

FIG. 1 is a front, perspective view of a solar handbag showing our new design, according to a first embodiment; FIG. 2 is a front side elevation view thereof; FIG. 3 is a back elevation view thereof; FIG. 4 is a left side elevation view thereof; FIG. 5 is a right side elevation view thereof; FIG. 6 is a top elevation view thereof; and, FIG. 7 is a bottom elevation view thereof.

The broken lines showing portions of the bag are for the purposes of illustrating environment and forms no part of the claimed design.
